N. Y., a corporation of New York

Application August 28, 1946, Serial No. 132,939

Term of patent 14 years

(Cl. D31—4)

To all whom it may concern:

Be it known that I, Elmer Wodetzky, a citizen of the United States, residing at Lynbrook, in the county of Nassau and State of New York, have invented a new, original, and ornamental Design for Line Guide for Fishing Rods, of which the following is a specification, reference being had to the accompanying drawing, forming a part thereof.

Fig. 1 is a top plan view of a line guide for fishing rods, showing my new design;

Fig. 2 is a side elevational view thereof;

Fig. 3 is a bottom plan view thereof; and
Fig. 4 is an end view thereof.

I claim:

The ornamental design for a line guide for fishing rods, as shown.

ELMER WODETZKY.
